Foster Wheeler Corporation, New York, N. Y.,
a corporation of New York

Application July 29, 1939, Serial No. 287,291

3 Claims. (Cl. 122—473)

1

This invention relates to steam generators and superheaters.

The invention provides a novel arrangement of steam generating and steam superheating elements which will produce readily and efficiently superheated steam at various rates of steaming, the arrangement being such that the degree of superheat may be varied as desired throughout the load range of the generator.

The invention will be understood from the following description when considered in connection with the accompanying drawings forming a part thereof, and in which:

Fig. 1 is a simplified, vertical sectional view, more or less diagrammatic, of a steam generator and superheater embodying the invention, the section being taken on the line 1—1 of Fig. 2, and

Fig. 2 is a horizontal sectional view, taken on the line 2—2 of Fig. 1.

Like characters of reference refer to the same or to similar parts throughout the several views.

Referring to Figs. 1 and 2 of the drawings, the generator and superheater illustrated includes a setting 5 having a front wall 6, a rear wall 7, side walls 8 and 9, a roof 10 and a floor 11. A steam and water drum 12 is disposed in the upper part of the setting at one side thereof, and a lower or water drum 13 is disposed below and in vertical alignment with the upper drum 12. A vertical bank of steam generating tubes 14 connects the drums 12 and 13, and a bank or group of tubes 15 having their vertically extending portions spaced from the bank of tubes 14, also connect the upper and lower drums.

In the form shown, the space between the enclosing walls of the setting and the bank of tubes 14 is partitioned to provide a boiler furnace 16 and a superheater furnace 17. A partition wall 18 of refractory or other suitable material extends normally from front wall 6 to a point short of the rear wall 7 and serves to separate the boiler and superheater furnaces. As shown, the tubes 15 are arranged for the most part in two vertical rows which extend in a direction parallel to the axes of the drums 12 and 13, and a partition wall 19 of refractory or other suitable material extends from the rear wall 7 between these rows of tubes to a point short of the front wall 6. Another partition wall 20 similar to wall 18, extends from the front wall 6 between the first two rows of tubes toward the furnace side of the bank 14 to a point short of the rear wall 7.

The boiler furnace 16 is fired by one or more fuel burners 21 which are arranged to burn pulverized coal, oil, or gas or any combination of

2

these fuels. The superheater furnace is independently fired by one or more burners 22, similar to burners 21. The front and rear walls of the boiler and superheater furnaces are lined with tubes which are connected into the boiler circulation. The front walls are lined with tubes 23 which extend between upper and lower headers 24 and 25, header 24 being connected to the upper drum 12 by suitable connections not shown, while header 25 is connected to the lower drum 13 by a plurality of connections 26. Tubes 27, similarly arranged and connected, line the rear wall 7 of the setting, which constitutes the rear walls of the boiler and superheater furnaces. Tubes 28 line the boiler furnace side of the partition wall 18, the upper ends of the tubes being connected to a header 29 which is connected to upper drum 12 by tubes 30 which line the roof of the furnace 16. The lower ends of alternate tubes 28 are connected to the lower drum 13, while the lower ends of the other tubes 28 are connected to a header 31 disposed on the floor 11 of the setting at the lower end of side wall 8. The lower ends of the horizontal portions of the tubes 28 lie below the refractory bottom 32 of the two furnaces 16 and 17. Header 31 is connected to the lower drum by connections 33 which extend along the floor 11 of the setting.

The superheater 34 in furnace 17 is arranged in the form of an inverted U with a partitioned inlet and outlet header 35 and return headers 36 and 37. The header and tube arrangement are such as to provide a plurality of passes of the steam through the superheater. The superheater tubes line the side walls and roof of the superheater furnace 17 from the front wall 6 rearwardly for a distance equal to the length of the partition wall 18 and thus are shielded from the heat generated in the boiler furnace. If desired, the tubes 28 may be omitted, in which event the refractory wall 18 will perform the entire shielding function. Steam is conducted from the steam drum to the inlet of the header 35 through line 38 and superheated steam leaves the superheater from the outlet end of header 35 through a line not shown.

Water wall tubes 40 line the rear end of side wall 8 between the rear end of the superheater 34 and the rear wall 7 of the setting. These tubes are connected into the boiler circulation by suitable means not shown. The tubes 15 which are disposed between the forward end of partition wall 19 and front wall 6, are arranged to provide a slag screen 41 for the gases leaving the furnaces 16.

In operation, the products of combustion or gases produced by the firing of one or more burners 21 flow from the front to the rear portion of the boiler furnace 16 where they make a turn of 180° and return to the front end of the boiler furnace, at which point they make a 180° turn in a horizontal direction and flow over slag screen 41 and into and through the passage 42 and into the rear end of the main bank 14 of boiler tubes, through the bank of boiler tubes, and out the flue 43 at the front of the setting. When the superheater furnace 17 is fired, the gases or products of combustion produced by the operation of the one or more burners 22, flow through the superheater furnace from the front to the rear thereof and pass from the furnace through passage 44 between the rear end of partition wall 18 and the rear wall 7 of the setting. These gases then flow through the boiler furnace 16 from the rear portion to the front end thereof, along with the gases produced by the one or more burners 21 and flow over slag screen 41 through passage 42 and over the main bank 14 of boiler tubes and out the flue 43.

The number of burners 21 and burners 22 in operation at any one time will depend upon the load on the generator and the required temperature of the steam. Each of the burners 21 and 22 may be controlled in the usual manner to provide for the different rates or intensities of firing. By varying the number of burners in operation in each furnace, or by varying the intensity of firing of the burners, or both, the desired degree of superheat at any load may be obtained.

By the use of the refractory partition wall 18, the superheater and its elements are completely shadowed from the gases in the boiler furnace 16. By causing the gases from the furnaces 16 and 17 to flow through the relatively narrow gas passage 42 prior to entering the boiler tube bank 14, slag elimination is facilitated, due in part to the cooling effect on the gases by the boiler tubes 14 and 15 which line the walls of this passage.

Changes may be made in the form, location and arrangement of the several parts of the forms of the invention selected for illustration. Although superheaters are shown which are heated preponderantly, if not solely, by radiant heat, the superheaters may be arranged so as to be partly radiant and partly convection superheaters. In view of the changes which may be effected in the embodiments selected for disclosure without departing from the principles of the invention, it will be understood that the invention is not to be limited excepting by the scope of the appended claims.

What is claimed is:

1. In a boiler having upper and lower drums interconnected by a bank of generating tubes and means including front and rear walls defining a

60

furnace space at one side of said bank; a wall dividing said space to form separate furnace chambers including generating tubes arranged in one or more rows extending across said space from said front wall to a point short of said rear wall and leaving a passage for gas flow from one of said furnace chambers to the other; a superheater in said one chamber having tubes arranged parallel to and closely adjacent the generating tubes in said dividing row; individual fuel feeding means for said chambers; and other generating tubes arranged in a row on said rear wall opposite the end of said dividing wall and forming one side of said passage.

2. Steam generating apparatus comprising a setting having front and rear walls, a bank of steam generating tubes at one side of the setting, dividing means including tubes connected in circulation with the steam generating tubes and dividing the space in the setting at one side of the steam generating tubes into a plurality of furnaces including a boiler furnace and a superheater furnace, a burner for firing each furnace located in the front wall of the setting, said means extending across said space from the front wall to a point short of the rear wall to provide a passage for gas flow from the superheater furnace to a boiler furnace, a superheater having tubes disposed adjacent a wall defining the superheater furnace and located substantially out of the path of the gases flowing through the superheater furnace, other generating tubes arranged in a row on said rear wall opposite the end of said dividing means and forming one side of said passage, and means for directing the flow of gases from said furnaces over the steam generating tubes.

3. Steam generating apparatus comprising a setting having front and rear walls, a group of steam generating tubes at one side of the setting, means including superheater tubes dividing the space in the setting at one side of the steam generating tubes into a plurality of furnaces including a boiler furnace and a superheater furnace, the superheater tubes being located substantially out of the path of the gases flowing through the superheater furnace, a burner for firing each furnace located in the front wall of the setting, said means extending across said space from the front wall to a point short of the rear wall to provide a passage for gas flow from the superheater furnace to a boiler furnace, superheater tubes on the wall of the superheater furnace opposite said first-mentioned means and located substantially out of the path of the gases flowing through the superheater furnace, and means for directing the flow of gases from said furnaces over the steam generating tubes.

FERNANDO FALLA.
